HOOD ORNAMENT OR SIMILAR ARTICLE
FOR A MOTOR VEHICLE

John Sneed, Detroit, Mich.

Application October 25, 1950, Serial No. 12,724

Term of patent 7 years

(Cl. D14—18)

To all whom it may concern:

Be it known that I, John Sneed, a citizen of the United States, residing at Detroit, Wayne County, Michigan, have invented a new, original, and ornamental Design for a Hood Ornament or Similar Article for a Motor Vehicle, of which the following is a specification, reference being had to the accompanying drawing, forming a part hereof.

Fig. 1 is a side elevational view of a hood ornament or similar article for a motor vehicle showing my new design.

Fig. 2 is a plan view thereof.

Fig. 3 is a fragmentary bottom view of Fig. 1 showing the vanes in full lines.

Fig. 4 is a sectional view taken on the line 4—4 of Fig. 1.

I claim:

The ornamental design of a hood ornament or similar article for a motor vehicle, substantially as shown.

JOHN SNEED.
